United States Patent Office.

JOHN W. CURTIS, FRANKLIN A. BRIGGS, AND MILTON O. COX, OF COLDWATER, MICHIGAN.

Design No. 4,150, dated June 14, 1870.

DESIGN FOR A CARRIAGE-STEP.

The Schedule referred to in these Letters Patent and making part of the same.

To whom it may concern:

Be it known that we, JOHN W. CURTIS, FRANKLIN A. BRIGGS, and MILTON O. Cox, of Coldwater, in the county of Branch and State of Michigan, have invented a new and original Design for Carriage-Steps; and we do declare that the following is a true and accurate description thereof, reference being had to the accompanying photograph, being a part of this specification.

The nature of our design relates to the construction of an ornamental step in cast-iron, to be placed at the

roadside, for use in entering or leaving a vehicle, mounting or dismounting from horse-back, and other like purposes.

We claim as our invention—

The design for a carriage-step, as shown.

JOHN W. CURTIS.
FRANKLIN A. BRIGGS.
MILTON O. COX.
